UNITED STATES PATENT OFFICE.

JACOB T. LANDGRAF, OF MACOMB, ILLINOIS, ASSIGNOR TO AMERICAN STEEL PRODUCTS CO., OF MACOMB, ILLINOIS, A CORPORATION OF ILLINOIS.

INCUBATOR.

Application filed December 24, 1923. Serial No. 682,524.

To all whom it may concern:

Be it known that I, JACOB T. LANDGRAF, citizen of the United States, residing at Macomb, Illinois, have invented certain new and useful Improvements in an Incubator; and I do hereby declare the following to be a full, clear, and exact description of the invention, such as will enable others skilled in the art to which it appertains to make and use the same.

My invention relates to the class of incubators in which the temperature is regulated by means of a thermostat, and in one of its general objects aims to provide a novel arrangement for controlling the temperature within the incubator partly by varying the temperature within a hot air chamber adjacent to the hatching chamber of the incubator, and partly by varying the extent to which fresh air is drawn through this hatching chamber. For this purpose, my invention provides an air chamber above the hatching chamber, provides air inlets and outlets for this chamber, and arranges certain of the said inlets so that the draft of the lamp or of the heater employed as part of the incubator can produce a draft through this chamber either from a draft tube disposed over the heater or from the outer air.

In another aspect, my invention provides a novel mounting for a thermally expansible hollow diaphragm (or plurality of diaphragms) employed in connection with an incubator, and also provides novel construction of the parts which are responsive in movement to the expansion or contraction of such a diaphragm and which control the movement of air through various parts of the incubator. Furthermore, my invention provides a novel arrangement of various other portions of the incubator, together with novel detail features which will appear from the following specification and from the accompanying drawing.

In the drawings, Fig. 1 is a perspective view of an incubator embodying my invention.

Fig. 2 is an enlarged central and vertical section through the same.

Fig. 3 is a somewhat reduced horizontal section taken from the line 3—3 of Fig. 2.

Fig. 4 is a similarly reduced horizontal section taken from the line 4—4 of Fig. 2.

Fig. 5 is a similarly reduced horizontal section taken from the line 5—5 of Fig. 2, looking upward.

Fig. 6 is an enlargement of a portion of Fig. 2, showing how the cover parts are secured to each other and how the cover is supported.

In the embodiment of the drawings, the incubator of my invention comprises a casting having a substantially flat bottom 1 provided near its outer edge with a plurality of air inlet openings 2 and secured at its periphery to a cylindrical shell 3 which forms the outer side wall of the incubator. The bottom 1 has suitably indented plates 4 secured to its lower face to afford socket formations 5 entered by the horizontally bent upper ends 6 of legs 7, each of which legs desirably is bent from a single strand of wire and has its said upper end portions 6 slidably inserted in the said sockets so that the legs can readily be detached to permit the compact packing and shipping of the incubator. The bottom 1 also has clips 7 formed from it for receiving the bent upper ends of a pair of links 8 which are secured to the reservoir 9 of the oil lamp employed with the heater, so as to suspend this lamp from the bottom plate which in turn is rigidly supported by the said legs. The lamp has a chimney 10 extending through a central opening in the bottom plate 1 into a draft tube 11 which is secured to this bottom plate and extends upward from the same to a point which desirably is considerably below the top of the outer side wall 3.

Loosely surrounding this draft tube 11 is a collar 12 which rests upon the upper surface of the bottom plate 1 and which has the inner edge of an annular wire screen 13 secured to the same at some distance above the lower end of the said collar. The outer end of the screen desirably has a metal binding 14 adapted to rest on inwardly directed lugs 15 formed from an inner shell 24. This inner shell is somewhat smaller in diameter than the outer shell 3 so as to provide an air jacket between the two, and the inner shell is desirably flared outwardly at its upper end as shown at 25 in Fig. 2 so as to have its upper end portion secured to the said outer wall 3, while the outwardly directed portion 25 of the inner shell also affords an annular ledge for supporting the

removable cover portion of the incubator.

This removable cover portion carries the thermostatic control device, together with a chimney 20 afford a flue in the extension 5 of the lamp chimney 10. For this purpose, I am here showing the detachable top member as comprising a lower plate 18 spaced from an upper plate 19 so as to provide a hot air chamber between the two, this upper 10 plate 19 being desirably bowed downward adjacent to its outer edge and secured to the lower plate 18 at its periphery by a seaming operation as also shown in Fig. 2. The hollow chamber thus formed in the cover has 15 associated with it a flue tube 20 which extends through an aperture in the bottom 18 of the hollow cover and which desirably terminates substantially flush with a corresponding aperture in the top plate 19, this 20 flue tube 20 being desirably of such a length as to extend around and somewhat below the upper end of the lamp chimney 10. Extending into this flue tube 20 from the said air chamber in the cover member are a plurality of tubes 21 which extend radially outward from the flue tube for a considerable distance. Each of these radial tubes desirably rests upon the bottom plate 18 of the cover member and opens into the said hot 25 air chamber at a distance from the edge of the cover. This hot air chamber also has apertures 22 substantially at its periphery and near the bottom of the chamber, such apertures being here shown in the form of 30 openings in the downwardly bent outer portion of the top of the cover member, and these apertures 22 are out of alinement with the radial flue tubes 21.

Mounted within the hatching chamber 40 (which is inclosed by the substantially horizontal plates 1 and 18 and the inner shell 24) is a thermostat which has as its actuating member one or more hollow and thermally expansible diaphragms 23 filled with a 45 liquid adapted to vaporize at a temperature below that to which the temperature in the hatching chamber is to be restricted. This actuating member is here shown as comprising a pair of superposed hollow diaphragms 50 23 supported by the lower arm 16 of a fork 34, this fork being clamped to a vertical tube 25' which extends through the cover member into the incubator chamber and which affords a guide for a thrust stem 26. 55 The thrust stem may be a simple rod resting loosely on the upper diaphragm and extending at its upper end through a base of a forked bearing 27 which has a damper-carrying lever pivoted to it. This lever has an 60 adjusting screw 28 threaded through it and engaging the upper end of the thrust stem 26, the thrust stem and screw being desirably rather close to the pivotal mounting of the levers so that the lever will greatly increase the extent of movement over that af- 65

fording by the expansion and contraction of the diaphragms. The free end of the lever is desirably formed into a hook 29 overhanging the draft flue 20 and supporting a damper 30 which is larger in diameter than the upper end of the said draft flue and which normally closes the opening in the top of the cover.

With the parts thus arranged, the screw 28 is initially adjusted so that the thermostatic diaphragms will not lift the damper or closure member 30 out of its normal closure position of Fig. 2 until the temperature in the hatching chamber exceeds a certain degree. With the flue outlet through the top 70 of the incubator thus closed, the hot gases 75 rising from the lamp pass through the radial tubes 21 into the hot air chamber within the cover and reach the outer air through the outlet openings 22. In doing so, these hot 80 gases first heat the radial tubes 21 which rest on the bottom plate 18 of the cover and then travel further over the upper face of this cover so as to heat the latter and hence 85 warm the hatching chamber under this plate 18. To increase the effectiveness of this 90 heating action, I desirably locate the outlets 22 close to the bottom plate 18, and by having these outlets out of alinement with the radial tubes 21, I compel the air currents 95 to follow circuitous routes as shown for example by the arrows in Fig. 3.

As the temperature in the hatching chamber increases, the expansible diaphragms or so-called "thermostatic wafers" expand and move the lever through the action of the thrust member 26, thereby raising the damper or closure member 30 and affording a direct flue outlet through the cover. The 100 hot gases then follow the shorter path by issuing either wholly or in part through the upper end of the flue tube 20 instead of their all passing through the hot air chamber within the cover, and hence do not continue to heat this chamber. Indeed, if the 105 rise of temperature within the hatching chamber is such as to effect a considerable raising of the damper 30, the upward movement of the hot gases through the flue tube 20 also produces an ejector action by drawing 110 warm air from the hot air chamber into this flue tube, this warm air being then replaced by cold air entering through the lateral apertures 22.

The raising of the closure member 30 also affects the passage of air through the bore of the draft collar. As long as the upper end of the vertical flue tube 20 is closed, the relatively small bores of the radial tubes 21 as well as their horizontal position retard the draft producing effect of the flue tube 20. Consequently, some of the warmed air surrounding the lamp chimney 10 will rise through the bore of the collar 11 and will 115 pass up between this collar and the flue tube 120 125 130

20 so as to enter the hatching chamber and increase the heating of the latter. When the closure member 30 is raised, the increase in the upward draft through the flue tube 20
 5 will cause more of this heated air to pass into the flue tube between the bore of the latter and the upper end of the chimney, thereby diverting freshly warmed air from the hatching chamber. Indeed, an unusual
 10 lift of the damper 30 may even increase the flue draft to such an extent as to cause a down draft around the flue tube through the collar 11, thereby drawing warm air from the hatching chamber, this being replaced by cool air entering through the bottom openings 2. However, the height to which the draft tube 11 extends into the hatching chamber retards this last named action so as to avoid an undue cooling of the eggs.

When the lamp is first lighted, it heats the hatching chamber in three ways, namely by warming the air under the bottom of the incubator, by heating the flue tube and the upper hot air chamber, and by heating air which passes into the hatching chamber through the collar 11. Owing to this three-fold action, I can raise the hatching chamber to the desired temperature in a relatively short time, and since the lateral wall of the hatching chamber is air jacketed, while the top and bottom of this chamber are both heated, the needed minimum temperature in the hatching chamber is easily maintained.
 25 Furthermore, since the flue tube radiates heat both into the hatching chamber and into the upper hot air chamber, and since the hot gases are kept close to the bottom plate of the cover while passing through the latter, I utilize the heating action of the lamp to an unusual degree. Consequently, my simple construction affords an incubator which is highly efficient as well as quick in its response to temperature variations in the hatching chamber.

By extending the draft flue 20 into the draft tube 11 for a considerable distance, I avoid drawing an undesirably large amount of fresh air through the hatching chamber and hence do not cause the action of the thermostat to retard the rate of incubation, although I do secure a sufficient air movement through the hatching chamber to maintain the desirable freshness of the air in the same. Then the balance of any needed cooling effect is secured by my cooling the air within the chamber of the cover after the manner above described.

By adjoining the inner and outer lateral walls of the incubator through a horizontal flange or ledge 25, I provide a suitable support for the cover and one which will permit the adjoined outer edges of the cover parts to fit snugly into the resulting cup shaped formation as shown in Fig. 6, the

cover being readily drawn out of such a snug seating by a lifting ring 35. The lugs 15 on the inner wall afford a simple outer support for the screen 13 upon which the eggs are placed, and the upward extension 70 of the collar 12 which supports this screen at its inner edge affords a convenient handhold for enabling the screen to be withdrawn or replaced in position. Moreover, since both the flue tube and the entire thermostatic control arrangement are mounted on the cover, the mere removal of the latter permits free access to the hatching chamber and the entire arrangement is such as to require no skill or previous experience for its 80 handling.

However, while I have illustrated and described my invention in an embodiment including many highly desirable details of construction and arrangement, I do not wish 85 to be limited to these, since many changes might obviously be made without departing either from the spirit of my invention or from the appended claims.

I claim as my invention:—

1. In an incubator, a casing having a closed bottom, an inner shell in the casing seated on the bottom of the casing and formed at its upper end with an outwardly directed portion disposed at a distance below the casing top and engaging the casing sides to space the inner shell therefrom and to provide a ledge, a draft tube extending upwardly from the casing bottom, a collar seated on the casing bottom and spacedly surrounding the draft tube, a foraminous member carried by the collar and engaged with the casing sides, lugs struck out from the inner shell to support said member, a cover having a top and spaced bottom the marginal edges of which extend downwardly and are connected together and seat on said ledge, a central depending chimney connected to the cover and extending into the collar, and a series of radial flue tubes 100 extending through the chimney and having their outer ends spaced from the cover sides. 105

2. In an incubator, a casing having a closed bottom, an inner shell in the casing seated on the bottom of the casing and formed at its upper end with an outwardly directed portion disposed at a distance below the casing top and engaging the casing sides to space the inner shell therefrom and to provide a ledge, a draft tube extending upwardly from the casing bottom, a collar seated on the casing bottom and spacedly surrounding the draft tube, a foraminous member carried by the collar and engaged with the casing sides, a hollow cover seated on the ledge, a central depending chimney connected to the cover and extending into the collar, and a series of spaced radial flue tubes extending through the chimney and having their outer ends spaced from the 110 115 120 125 130

cover sides, the cover sides having outlets arranged at points in alinement with the spaces between the flue tubes.

3. In an incubator, a casing having a hatching chamber, a heating chamber above the hatching chamber, a central chimney extending through the heating chamber and into the hatching chamber, heating means in communication with the chimney, and a series of spaced radial flue tubes extending into the chimney and having their outer ends spaced from the sides of the heating chamber, the heating chamber having outlets in its sides arranged at points in alinement with the spaces between the flue tubes.

4. In an incubator, a casing having a closed bottom, an inner shell in the casing seated on the bottom thereof and having an

outwardly directed upper portion disposed at a distance below the casing top and engaging the casing sides to space the inner shell therefrom and to form a ledge, a hollow cover having a rim seated on the ledge, a central depending chimney carried by the cover, a series of spaced radial flue tubes in the cover interior extending into the chimney and having their outer ends spaced from the sides of the cover, the heating chamber having outlets in its sides arranged at points in alinement with the spaces between the flue tubes, and a heater communicating with the chimney.

Signed at Macomb, Illinois, December 10th, 1928.

JACOB T. LANDGRAF.
